UNITED STATES PATENT OFFICE.

FRANK D. ARTHUR, OF SCARBOROUGH, NEW YORK.

BODKIN.

SPECIFICATION forming part of Letters Patent No. 546,128, dated September 10, 1895.

Application filed December 10, 1892. Serial No. 454,800. (No model.)

To all whom it may concern:

Be it known that I, FRANK D. ARTHUR, a citizen of the United States, residing at Scarborough, in the county of Westchester and State of New York, have invented a new and useful Improvement in Bodkins, of which the following is a specification.

My invention relates to improvements in bodkins in which, instead of an eye to hold the ribbon, tapes, or other material to be used, spring-jaws are used, brought together by a sliding clasp, as more fully described below.

The objects of my invention are to hold the ribbon, tapes, or other material flat without twisting while being drawn through lace or other material, and also the saving of the material used, and to hold the ribbon in such a manner that it will not slip from the needle. I attain these objects by the means illustrated in the accompanying drawings, in which—

Figure 1 is a view of the bodkin before being bent into shape. Fig. 2 is a view in perspective of the bodkin bent into shape ready for use.

Similar letters refer to similar parts throughout both views.

The metal or other suitable material is cut or formed into the shape shown in Fig. 1. Teeth *b b* are bent over sufficiently to form hooks for the purpose of holding the ribbon more firmly. (See Fig. 2.) The device is then bent over on itself at point *a*, which then becomes the point of the bodkin, until it as-

sumes the shape shown in Fig. 2. In this position teeth *b b* overlap each other. Clasp *d* is then put on so it will slide in recesses *c c*. (See Fig. 2.) Clasp *d* is made of metal, having rounded edges to prevent it catching in lace when being used.

To use device, place the ribbon, tape, or other material to be used between teeth *b b*; push clasp *d* toward *b b* as far as it will go, causing jaws to come together, thus firmly holding the material in place.

I am aware that prior to my invention bodkins have been made with spring-jaws. I therefore do not claim such invention, broadly; but

What I do claim as my invention, and desire to secure by Letters Patent, is—

The bodkin, comprising a strip of spring metal folded upon itself, the folded parts being provided with correspondingly narrowed portions for the reception of a sliding clasp and the free ends of the folded parts being provided with holding jaws turned inwardly and arranged to lap past each other when the jaws are closed, and a clasp surrounding the narrowed portions and adapted to slide toward and away from the holding jaws to lock and release them, substantially as set forth.

FRANK D. ARTHUR.
